ABSTRACT: A slitter-scoring machine used in the production of corrugated paperboard having means for presetting one set of slitting heads and scoring heads during operation of another set of such heads comprising two sets of shafts upon which the heads are mounted with the shafts secured between a pair of circular side frames to form a spool arranged for rotation about a central trunnion so that with the spool in one circumferential position one set of shafts with the heads thereon are in position for acting upon an advancing web of paperboard while the other shafts are in an inactive position with a set of yokes being provided to engage the inactive heads and move them to preselected lateral positions across the width of the machine so that upon completion of the order being processed, the spool may be rotated to bring the preset heads into engagement with the web to produce a succeeding order.

FIG. 29

PRESETTABLE SLITTER-SCORER APPARATUS

BACKGROUND OF THE INVENTION

1. Field of the Invention

This invention relates generally to cutting and more particularly to cutting other than completely through the work such as by plural rotary scoring with typical cutting.

2. Description of the Prior Art

In the processing of sheet material, especially an endless web of corrugated paperboard, it is highly desirable to form the web as wide as possible and then slit the web into narrower strips. Score lines are also usually made in each strip of corrugated paperboard at about the same time as the web is slit into preselected widths. The web-forming apparatus is operated on a continuous basis and the operation is interrupted only at such times as the slitting and scoring apparatus is adjusted to change the widths and lengths of the web material for the production of carton blanks of preselected size. It is now possible to make rapid adjustments in the apparatus for cutting the continuous web into lengths of preselected dimension. With the presently known slitting and scoring apparatus, however, a substantial amount of time is required to adjust the apparatus for changing the widths of the strips cut from the web of corrugated paperboard and the score lines impressed on the respective strips. It is, therefore, highly desirable to provide apparatus for slitting and scoring the continuously moving web of corrugated paperboard that may be rapidly adjusted to change the widths of the strips cut or slit in a continuously moving web. Apparatus which reduces the adjustment time minimizes the amount of waste incurred in the corrugated paperboard manufacturing. Where a substantial period of time is required to make the adjustment, portions of the continuous web are subject to burning in adjacent equipment.

Slitting and scoring of a continuously moving web has been accomplished by a slitter-scoring device that includes three separate sets of shafts supported by spaced-apart side frames. The shafts have slitting and scoring heads mounted thereon. While the heads of one of the shafts are slitting or scoring the moving web, the operator manually adjusts the heads on the other two sets of inactive shafts to the desired transverse dimension or spacing for subsequent slitting of the web into different-sized strips. This manual adjustment of the slitter-score heads is both time consuming and difficult to perform.

The setup time is excessive for the positioning or adjusting of the heads on the two sets of inactive shafts that are not slitting or scoring the continuously moving web. With short orders, that is, where only a short length of the continuous web is slit and scored into the preselected width, the operator does not have sufficient time to accurately adjust and set up the slitting and scoring heads on the inactive shafts for the next differently sized order. Interruption in the continuous process is usually required until the operator correctly adjusts the slitter-scoring heads on the inactive shafts.

A system for positioning the various slitting and scoring heads automatically during order changes was proposed by Lulie and Stewart as shown in U.S. Pat. No. 3,257,882. Their system encompasses several advantages over older methods but is still limited by the amount of time available from the time the web is transversely severed just prior to passing through the slitter-scoring apparatus and the time a new web is presented, such time being measured in seconds. Increasing demands are being made to reduce the time required to change over from an order of one size to another order of a different size. For example, it is now desirable to be able to change the positions of the various heads in the slitter-scoring in less than 10 seconds. Such demands are difficult to meet even by the system of Lulie and Stewart referred to above.

SUMMARY

Accordingly, an object of the present invention is to provide a slitter-scoring machine capable of being preset, to provide slitting and scoring heads in the desired position for engage-

ment with a corrugated paperboard web, within the time available for changing from one order to the next. This and other objects and novel features are accomplished by providing dual sets of shafts arranged in tandem upon which are mounted the various slitting and scoring heads so arranged that one set of heads is positioned for active engagement with the web while the remaining set is being preset to new lateral locations while out of active engagement with the web. Thus, the time required to present a correctly positioned set of heads for engagement with the web is only the time required to move one set of heads out of engagement while simultaneously moving the preset heads into engagement, for example, 2-3 seconds. The time available for repositioning the heads that are out of engagement in an inactive position is usually at least 5 minutes, which time is ample.

The preferred construction embraces a construction wherein the sets of shafts are arranged in a circle about an axis extending transversely across the line of web travel. By rotating the shaft sets about this axis, one set of shafts can be brought into an active position as the other set is removed to an inactive position. The heads on the inactive shafts are each engaged by a yoke which is then moved across the machine to a preselected location by a suitable control means provided for this purpose; thereafter the yokes are disengaged from the heads and returned to a "parked" position beyond the path of web travel in readiness for engaging the other set of heads when they are moved to the inactive position for positioning or setup.

Each set of shafts includes four shafts; two above the horizontally traveling web and two below. The heads mounted on the upper shafts cooperate with the heads mounted on the lower shafts to slit and score the web. One pair of the set of four shafts supports the scoring heads, preferably the pair nearest the approaching web, while the second pair supports the slitting heads. All of the heads could be mounted to one pair of shafts but, for reasons well known in the art, it is preferable that the circumferential velocity of the slitting heads be slightly faster than the line velocity of the web while the circumferential velocity of the scoring heads is about equal to web velocity.

Provision is also made for presetting an auxiliary set of slitting and scoring heads used for operating upon a web of about double the ordinary thickness as will be later explained; the ordinary thickness web being hereinafter referred to as "single-wall" and the double thickness web being referred to as "double wall."

BRIEF DESCRIPTION OF THE DRAWINGS

The above and further objects and novel features of the invention will appear more fully from the following detailed description when the same is read in connection with the accompanying drawings. It is to be expressly understood, however, that the drawings are not intended as a definition of the invention but are for the purpose of illustration only.

In the drawings wherein like parts are marked alike:

FIG. 1 is a side elevation of the slitter-scoring in cross section illustrating the position of pairs of active and inactive slitting and scoring shafts and the position of an upper yoke assembly when engaged with heads on the shafts and the position of a lower yoke assembly when disengaged from the heads;

FIG. 2 is a front view of the slitter-scoring in which the left-hand side shown externally to illustrate the action of the active shafts upon the web while the right-hand side is shown in cross section to illustrate the inactive shafts in position for engagement of yokes with the heads;

FIG. 3 is a schematic illustration of the sequence generally followed in positioning the heads by the yokes;

FIG. 4 is a schematic illustration of an end view of the power train showing the drive path for the active shafts;

FIG. 5 is a cross-sectional view of the power train taken along the line V-V of FIG. 4;

FIG. 6 is a side elevation of the drive input side of the slitter-scoring (see right-hand side of FIG. 2) illustrating the power input to the power train of FIGS. 4 and 5 and a power input for opening and closing the yoke assemblies;

FIG. 7 is a side view in cross section of one pair of inactive shafts illustrating a pusher used to move the heads to a "park" position at the side of the slitter-scoring;

FIG. 8 is a cross-sectional view taken along the line VIII-VIII of FIG. 7;

FIG. 9 is a side view in cross section of one pair of shafts in the inactive position illustrating a yoke assembly used to position the heads along the shafts;

FIG. 10 is a cross-sectional view taken along the line X-X of FIG. 9;

FIG. 11 is a cross-sectional view taken along the line XI-XI of FIG. 9;

FIG. 12 is a schematic illustration of an end view of the right-hand power train for lateral movement of the yokes;

FIG. 13 is a cross-sectional view taken along the line XIII-XIII of FIG. 12;

FIG. 14 is a cross-sectional view taken along the line XIV-XIV of FIG. 12;

FIG. 15 is a schematic illustration of an end view of the left-hand power train for lateral movement of the yokes;

FIG. 16 is a cross-sectional view taken along the line XVI-XVI of FIG. 15;

FIG. 17 is a schematic illustration of an end view of a power train for operating the pusher of FIG. 7;

FIG. 18 is a cross-sectional view taken along the line XVIII-XVIII of FIG. 17;

FIG. 19 is a chart setting forth the sequence of functions performed in setting up the machine under three separate operating conditions;

FIG. 20 is a block diagram of an analog servosystem for automatically positioning the slitting and scoring heads in response to lateral dimensions entered into a plurality of operating dials;

FIG. 21 is a schematic diagram of a Kelvin-Varley bridge modified to include three potentiometers for "readout";

FIG. 22 is a schematic diagram of an electronic switching circuit for switching the positioning system from the "coarse" error signal to the "fine" error signal;

FIG. 23 is a schematic diagram of a mechanical chopper circuit for treating the composite signal from the "coarse-fine" circuit of FIG. 22;

FIG. 24 is a schematic diagram of a band-pass filter for treating the signal from the chopper of FIG. 23;

FIG. 25 is a schematic diagram of a preamplifier for amplifying the error signal from the band-pass filter of FIG. 24;

FIG. 26 is a schematic diagram of a class AB driver for treating the signal from the preamplifier of FIG. 25;

FIG. 27 is a schematic diagram of a phase-sensitive demodulator for detecting the polarity of the signal from the AB driver of FIG. 26;

FIG. 28 is a schematic diagram of a power amplifier for amplifying the signal from the demodulator of FIG. 27 and supplying a signal to clutches used to drive the head positioning yokes; and

FIG. 29 is a schematic diagram of the pushbutton controls used for dialing in positions for the heads and operating the machine.

DESCRIPTION OF THE PREFERRED EMBODIMENT

General

As best illustrated in FIGS. 1 and 2, the slitter-scoring of the present invention includes a spool assembly 10 that is trunnion mounted between a pair of frame assemblies 12L, 12R that are adapted for lateral movement upon bases 14L, 14R. The spool 10 includes four pairs of shafts 16 (A, B, C, and D) mounted for rotation between subframe assemblies 18L, 18R of which shaft pairs 16A and 16B are shown in the active position in engagement with web 20 and pairs 16C and 16D are shown in the inactive position for setup.

The pairs of shafts 16A and 16D are each provided with cooperating upper and lower slitting heads 22 (double-wall heads denoted 22-D) for dividing web 20 into two or more strips moving side by side in the known manner. The pairs of shafts 16B and 16C are provided with cooperating upper and lower scoring heads 24 (double-wall heads denoted 24-D) for longitudinally scoring the web prior to its division into strips by the slitting heads.

The slitting and scoring heads 22, 24 referred to herein are conventional other than being modified for engagement with yokes to be subsequently described. It should be understood that heads of other types may be used equally well with the present invention when modified in accordance therewith.

Yoke assemblies 26U and 26L are provided for laterally positioning the heads 22, 24 across the shafts 16 that are in the inactive or setup position. The upper yoke assembly 26U located above web 20 includes a yoke 28 for each pair of cooperating heads 22 or 24. Means are provided for raising (opening) the yoke assembly during rotation (indexing) of spool 10 so that the pairs of heads being brought into setup position will clear the yokes 28. Thereafter the assembly is lowered (closed) to bring the yokes 28 into engagement with the heads. A threaded rod 30 passes through each of the yokes 28 and is operatively connected thereto to move each yoke a predetermined distance across the pairs of shafts 16 thereby moving the associated heads to the desired location. A pusher plate 32 surrounds each pair of shafts 16 and is slidably driven across the shafts to move all the heads 22, 24 into a "park" position beyond the edge of the web 20. The yokes 28 engage the heads in their park positions for subsequent positioning across the shafts; after such positioning, the yokes are returned to the park position.

Stops 34, illustrated schematically in FIG. 3, are provided to limit the travel of the heads 22, 24 and yokes 28 to an extreme lateral or zero parked position. Thus, alignment of the yokes with the heads is assured. Once the heads have been moved to their operative position on the shafts, they are locked in place by hydraulically expanding the shafts into frictional engagement with the inner bores of the heads as will be subsequently explained.

The auxiliary or double-wall heads are stored (parked) on the opposite side of the machine from the single-wall heads as shown schematically in FIG. 3. An operator can select and automatically position either the single or double-wall heads which is of great value since, in conventional machines, it is necessary to first completely dismount the single-wall heads from the shafts and thereafter mount the double-wall heads on the shafts.

The lower yoke assembly 26L below web 20 operates the same as described above for upper yoke assembly 26U.

Operation

Suitable controls, to be subsequently described, are provided to enable an operator to perform the various functions required to set up the machine by actuating the control switches provided.

For a better understanding of the machine, FIG. 19 is provided to set forth the sequence of functions performed in setting up the machine under three separate operating conditions. When read in conjunction with the schematic illustration of FIG. 3, the setup functions become quite evident. The double-decker mentioned in the chart of FIG. 19 is not shown in the drawings but is conventional as is the manner in which the web is cut prior to indexing the spool 10. The web 20 is usually decelerated and cut laterally on the fly; the web ahead of the cut continues at full speed so that a gap is opened up between it and the web behind the cut. As the fast-traveling web clears the slitter-scoring, the spool 10 is indexed to place the preset heads in position for operating upon the slow-moving advancing web which is then accelerated after indexing has occurred.

If preferred, the web may be completely stopped and cut and the forward portion drawn out of the slitter-scoring before indexing.

Detailed Construction

For clarity, a detailed construction will be described for each of the machine assemblies and parts previously generally described.

Spool Assembly 10

As best illustrated in FIGS. 1, 2, 5, and 18, spool assembly 10 includes a pair of spaced subframe assemblies 18L, 18R between which four pairs of shafts 16 are mounted for driven rotation. Subframes 18L, 18R are connected by four spacer bars 36 to form a rigid spool structure 10. Spacer bars 36 preferably include reduced diameter end portions 37 which pass through subframes 18L, 18R (See FIG. 18) and are secured by a threaded screw 38 passing through a retaining washer 39 and into the bar.

The four pairs of shafts 16 are located circumferentially within the perimeter of subframes 18L, 18R as best illustrated in FIG. 1. The pairs of shafts 16A, 16B are aligned diametrically opposite the center of subframes 18L, 18R to define a path of travel for web 20. Obviously, when spool 10 is rotated (indexed) 90°, the pairs of shafts 16C, 16D define the path of travel of web 20. The individual shafts of the pairs are spaced from each other the correct distance to permit coaction between the heads 22, 24 for operation on the web as well understood by those skilled in the art.

Referring now to FIG. 5, each of the shafts 16 is made from a tube 40 with journals 42 secured in each end thereof by threaded screws 44. The shafts are journaled for rotation in suitable bearings 46 contained within bearing housings 48 and 50 which are retained in subframes 18L, 18R by retaining rings 52. Conventional shaft seals 54 are used between the journals 42 and bearing housings 48, 50 to permit the use of lubricant within the subframes 18L, 18R.

Each pair of shafts 16 is provided with intermeshing spur tooth gears 56 mounted for rotation with journals 42 and held in place by collars 58 fastened to the journals by screws 60. A gear motor 62 is provided for driving shafts 16 and is mounted to side frame 12R by screws 64. Gear motor 62 includes an output shaft 66 on which a spur gear 68 is mounted for rotation. If desired, gear 68 may be connected through appropriate gear boxes (not shown) to a line shaft which is usually provided alongside the double-backer. This system assures that the slitter-scoring will track the speed of the double-backer whereas gear motor 62 must have conventional adequate controls to make it track double-backer speed. Gear 68 is held in place by a washer 70 and screw 72. An idler gear 74 is mounted for rotation by a bearing 76 about a mounting stud 78 secured in side frame 12R by a screw 80. Gear 74 is held in place by a washer 82 and screw 84. Idler gear 74 is located to place gear 68 and one of the gears 56 in driving relation.

The drive path provided by the power train just described is illustrated schematically in FIG. 4. The motor output drive gear 68 is located along the axis of rotation 69 of spool 10. Idler gears 74, of which two are provided, being mounted to side frame 12R, remain stationary; However, gears 56, being mounted to shafts 16, move with spool 10 when it is indexed along the path from point A to point B. Accordingly, it can be seen that only the shafts 16 in the active position for operation on web 20 are driven by output gear 68 through idler gears 74. Gears 56 on the shafts 16 in the setup position are out of mesh with idlers 74 so that these shafts do not rotate during setup. When spool 10 is indexed, the gears 56 that are in mesh with idler gears 74 go out of mesh and the gears 56 on the remaining shafts 16 go into mesh to drive the shafts 16 in the active position.

As previously mentioned, it is desirable that the circumferential velocity of the slitting heads 22 be greater than the circumferential velocity of the scoring heads which is about equal to the lineal velocity of web 20. Faster rotation of slitting heads 22 is achieved by a smaller reduction gear ratio between the output gear 68 and the gears 56 mounted to the shafts 16A, 16D carrying the slitting heads 22. That is, these gears have fewer spur gear teeth than the gears 56 mounted on shafts 16B, 16C. The choice of gear ratios to provide the velocities desired is well understood by those skilled in the art.

The heads 22, 24 are conventional except for modifications to fit yokes 28 as will be subsequently described. Such heads are usually made as a single unit and then split diametrically to form two identical halves which are placed around shafts 16 and then bolted together to form a complete head. The heads 22, 24 of the present invention are made in like manner and are provided with a bore large enough to permit the heads to freely slide along the shafts 16 and small enough to prevent undesirable wobbling.

10 The heads 22, 24 are locked in position along the shafts 16 by hydraulically expanding the shafts so that the expanded shaft frictionally engages the bore of the heads. This system is shown and described in a patent application Ser. No. 360,389, filed Apr. 16, 1964 by Warren A. Stewart and entitled "Fluid Pressure Operated Hub to Shaft Locking Means," now abandoned.

15 Briefly, the means for hydraulically locking the heads 22, 24 along shafts 16 includes making the clearance between the shaft and the bore of the heads such that frictional engagement occurs when the shaft is expanded by hydraulic pressure. Thus, the shafts must be hollow to form a reservoir for hydraulic fluid supplied under pressure from a suitable source by a conventional rotary union secured to the journal of the shaft. The thickness of the wall of the shaft is selected to permit a few thousandths of an inch diametral expansion without exceeding the elastic limit of the shaft material. Operation of the hydraulic locking arrangement is clearly illustrated in FIG. 5.

20 Use of the foregoing locking arrangement is not essential. Other locking arrangements may be used such as, for example, the expandable key arrangement disclosed in Nitchie U.S. Pat. No. 2,989,328 issued June 20, 1961.

25 In the present invention, conventional rotary shaft unions 84 are secured to the ends of shafts 16, see FIG. 5. Hoses 86 connect unions 84 to a source of fluid hydraulic pressure (not shown). The hollow interior of shafts 16 is filled with hydraulic fluid in fluid communication with the fluid supply. When hydraulic pressure is exerted by the supply, pressure of the fluid in the shafts 16 causes them to expand into frictional engagement with heads 22, 24 thereby locking them to the shafts. Conversely, when the hydraulic pressure is relieved, the shafts 16 contract thereby unlocking the heads 22, 24.

30 Referring now to FIG. 1, a raise and lower adjusting shaft 88 is provided for adjusting the tangential spacing between the 35 cooperating heads 22, 24 on the pairs of shafts 16. Such adjustment is desirable to space the heads closer together or farther apart to compensate for the different thicknesses of web that may be passed between the heads. Such adjustments are conventional.

35 The adjusting shaft 88 extends through both subframes 18L, 18R as shown in FIGS. 5 and 18. A spur tooth gear 90 is secured to each end of shaft 88 so as to be in mesh with similar teeth 92 provided on bearing housings 50. The centerline of the bore in housings 50 for journaling shafts 16 is made eccentric with respect to the centerline around which teeth 92 are formed. Thus, as housing 50 is rotated, shaft 16 moves closer to or farther away from the other shaft of the pair. Since adjusting shaft 88 extends between the bearing housings 50 on opposite sides of the machine, rotation of shaft 88 will simultaneously rotate housings 50 to assure circumferential alignment; this results in parallel alignment of the two shafts 16 of the pair.

40 To provide for rotation of shaft 88, it extends through the outer wall 94 of subframe 18L, see FIG. 18. A reduced end 65 portion 96 is provided with screw threads 98 for engagement with threaded nut 100. When nut 100 is tightened against wall 94, the shaft 88 is locked against rotation to prevent rotation that might occur from vibrations when the machine is running.

45 Since there is relative movement between subframe 18L and main frame 12L during indexing, shaft 88 cannot extend through the latter frame. A wrench 102 is provided which has one end 104 adapted to engage a square or hexagonal portion 106 formed on the end of shaft 88 for rotating the shaft. The other end 108 of the wrench 102 is adapted to engage the nut 100 for loosening and tightening the nut. An opening 110 is

provided in frame 12L to provide access to nut 100 and shaft 88.

The eccentric housings 50 and cooperating adjusting shafts 88 are provided for the upper shafts of the pairs of shafts 16 when the latter are in the operating position shown in FIG. 1. Thus, eccentric movement of upper shafts 16 does not affect the mesh of the gears 56 on the lower shafts with the idler gears 74 which drive the shafts from drive gear 68.

Again referring to FIG. 18, it will be noted that shaft 16 terminates just beyond bearing 46; this bearing is retained by a washer 112 secured to the end of the shaft by a threaded screw 114.

As shown in FIG. 1, spool 10 is indexed around central axis 69. This is accomplished by providing trunnions 116R and 116L on main frames 12R and 12L as best shown in FIGS. 5 and 18. Cooperating journals 118R and 118L are provided on subframes 18R, 18L respectively of spool 10; thus, the spool can rotate around trunnions 116R, 116L.

A spur tooth gear 120 is mounted around trunnion 116R in a space provided between frame 12R and subframe 18R and is secured to journal 118R by a number of threaded screws 122. The corresponding space between the left side frame 12L and subframe 18L is filled with a spacer 124 likewise secured to subframe 18L by screws 122.

A spur tooth gear 126 is provided for driving gear 120 to index spool 10 around axis 69. Gear 126 is secured in the conventional manner to the output shaft 128 of a gear motor 130 which is in turn secured to main frame 12R by screws 132 (also see FIG. 6). Thus, when indexing is to be performed, a pushbutton switch is provided in the control circuit (to be subsequently described) for starting motor 130 in the desired direction to rotate spool 10 a distance of 90°. The motor 130 may be controlled to turn the required number of revolutions. Preferably, a stop is provided (not shown) to limit the rotation of the spool.

To attain exact alignment of spool 10 in either of its A and B index positions, a tapered retractable pin 134 is provided for mating engagement with a tapered opening 136 in subframe 18R. Extension and retraction of pin 134 may be accomplished by an electric solenoid or hydraulic ram 138 secured to main frame 12R by screws 140. Thus, prior to indexing spool 10, ram 138 is energized to retract pin 134. After indexing, ram 138 is energized to extend pin 134. The tapered portions of pin 134 and opening 136 serve to align the spool relative to mainframe 12R and to lock the spool firmly in position.

It can be seen in FIGS. 5 and 18 that a number of openings 142, 144, 146, 148, 150, 152, and 154 are provided in the main and subframes to permit access to the interior of subframes 18L, 18R for assembly, inspection, and repair. Suitable covers, denoted by the opening number plus suffix c, are secured to the subframes to achieve an oiltight assembly so that the gear train therein can be oil lubricated. For clarity, illustration of these openings has been omitted from the other FIGS.

Frame Assemblies 12L, 12R

Frames 12L, 12R serve as supports for spool assembly 10, yoke assemblies 26U, 26L, and various motors and controls to be described. The spool is supported by the trunnion 116 and journal 118 arrangement previously described. Tie bars 156 (see FIGS. 1 and 2) are provided to space the frames 12L, 12R the proper distance apart and to establish a rigid unitary assembly. Bars 156 preferably include reduced diameter end portions 158 which pass through frames 12L, 12R and are secured by a threaded screw 160 passing through a retaining washer 162 and into the bar. This arrangement is illustrated for one of the bars in FIG. 2, the remaining bars being omitted for clarity.

As previously mentioned, yoke assemblies 26U and 26L are opened and closed to provide clearance between yokes 28 and heads 22, 24 during indexing of spool 10. The yoke assemblies are arranged to abut the main frames 12L, 12R in the closed position and to be spaced therefrom in the open position. FIG. 1 shows, for purposes of illustration, the upper yoke assembly

26U in the closed position and the lower yoke assembly 26L in the open position although it should be understood that opening and closing of the assemblies occurs simultaneously so that both assemblies are either open or closed at the same time.

5 The yoke assemblies each have a pair of vertical guide bars 164 secured thereto as shown in FIG. 12. The bars preferably include reduced diameter end portions 165 fitted within a thickened portion 166 of yoke assembly housing 168. Threaded screws 170 secure the guide bars 164 firmly to housing 168.

10 As seen in FIGS. 1 and 2, the vertical guide bars 164 on the upper and lower yoke assemblies 26U, 26L oppose each other in axial alignment. The bars extend through guide holes 172 provided in main frames 12L, 12R and into a hollowed out portion 174 formed in these frames. Within the hollow portion 174, a spur tooth gear 176 is provided along the axis of the bars 164 just below the path of travel of web 20. The gears 176, in the hollow portions 174 opposite sides of the machine, are connected for driven rotation by a drive rod 178 which is journaled in main frame flanges 180. The ends of guide bars 164 terminate in flat portions 182 on which are mounted conventional spur tooth racks 184 such as by threaded screws (not shown). The rack 184 on the upper bar 164 meshes with gear 176 on the outboard side of the gear and the rack 184 on the lower bar 164 meshes with the gear 176 on the inboard side of the gear. A top view in cross section appears in the lower portion of FIG. 5. Thus, as gears 176 are rotated counterclockwise, both upper and lower yoke assemblies 26U, 26L 20 will be closed and, conversely, as gears 176 are rotated clockwise, the yoke assemblies will be opened.

25 Close examination of the foregoing arrangement as viewed in FIG. 1 will reveal the advantage of the arrangement. That is, the weight of the lower yoke assembly 26L is counterbalanced by the weight of the upper yoke assembly 26U. Thus, the driving force needed for opening and closing the yokes is small; just enough to overcome inertia and friction between the various parts.

30 The arrangement for driving yokes 26U, 26L into their open and closed positions is shown in FIGS. 5 and 6. Conventional worm gear boxes 186 are mounted to the outer face of frame 12R, such as by screws 187, so that a worm wheel 188 within the box can be secured to the end of each drive rod 178 in the usual manner. Each worm gear box includes a worm 190 meshing with the wheel 188 and a shaft extension 192 connected to worm 190 and extending beyond the box 186. A drive shaft 194 connects the shaft extensions 192 through conventional shaft couplings 196 as shown in FIG. 6. A drive motor 198 is connected to one of the worms 190 by a shaft extension 200. Thus, as motor 198 is energized to run in the proper direction, it rotates the worms 190 to open or close yokes 26U, 26L through the foregoing elements of the arrangement. It should be understood that other arrangements can be devised to accomplish the same purpose with equal effectiveness.

Machine Bases 14L and 14R

35 The assembly of the main frames 12L, 12R supporting spool 10 is supported on machine bases 14L, 14R for lateral movement with respect to the path of travel of web 20. Lateral movement is desirable because web 20 tends to weave from side to side during its forward travel. Therefore, in order to keep the heads 22, 24 operating in the proper position on the web, the slitter-scoring is controlled for lateral movement automatically in response to lateral shifting of the web. Many such automatic controls are available. For example, a satisfactory type is described in Nitchie et al. U.S. Pat. No. 3,260,142 issued July 12, 1966. No further description is believed necessary except to say that the hydraulic actuator "85" described by 40 Nitchie et al. can be conveniently secured to one of the machine bases 14L, 14R with its output shaft attached to one of the main frames 12L, 12R for moving the assembly across the machine bases.

45 The means by which locomotion is achieved comprises four wheels 202 preferably bearing mounted for rotation about

axles 204 which are secured to the main frames 12L, 12R in any convenient manner. Each base includes a track portion 206 for guiding the wheels 202 accurately across the width of the web. Thus, actuation of the hydraulic actuator "85" mentioned above will move the entire slitter-scoring assembly across the bases 14L, 14R in a direction corresponding to the direction of movement of the actuator output shaft.

It should be understood that the lateral adjustment just described is not essential but is preferred for obvious reasons.

Yoke Assemblies 26U and 26L

The yoke assemblies 26U and 26L are identical except that assembly 26L is located beneath web 20 in mirror image relation with respect to assembly 26U above the web. Accordingly, the following description of assembly 26U applies equally to assembly 26L.

Yoke assembly 26U includes a housing 168 on each side of the machine which is supported on the top of frames 12L, 12R, as shown in FIG. 2, by guide bars 164 as previously described. The housings are linked together across the machine by a pair of support shafts 208 which are secured to the housings as shown in FIG. 14. Shaft 208 includes a reduced diameter end portion 210 passing through a thickened portion 212 of housing 168. A threaded screw 214 passing through a washer 216 and into the shaft completes the rigid connection. Although this connection is shown near the bottom of housing 168 in FIG. 14 for clarity, the actual locations are indicated by a pair of darkened dots in FIG. 12, such schematic indication also being made for clarity.

A yoke subassembly 28 is provided for each of the cooperating pairs of single-face heads 22, 24 and is itself supported on the shafts 208. As shown in FIGS. 9 and 10, each yoke 28 includes axially opposed arcuate guide surfaces 218 for engaging annular side surfaces 220 formed on the heads 22, 24. Thus, the only modification to almost any type of slitting or scoring head needed is the provision of surfaces 220 to permit engagement of yokes 28. As the yokes 28 are moved across the machine, they pull the heads 22, 24 with them.

The length of arcuate surfaces 218 is made in accordance with FIG. 9. Thus, by also referring to the lower half of FIG. 1, it can be seen that when yoke 26L is in its open position, yokes 28 are clear of their associated heads to permit indexing of spool 10. It should be understood that prior to such indexing, all of the yokes 28 have been moved to the parked position on the right-hand side of the machine that is illustrated in FIG. 2 and against stops 34. However, since not all of the heads 22, 24 may have been used in setting up a particular order, the yokes 28 associated with those heads not used will be engaged with those heads after indexing and closing of the yokes. Accordingly, these yokes must clear the heads with the yoke assemblies 26U, 26L in their open position prior to indexing.

It should also be noted that a radial clearance 222 must be provided between the heads 22, 24 and yokes 28 to compensate for the movement of one of the shafts 16 toward the other shaft of the pair needed for adjusting coaction between the heads as previously explained.

Lateral movement of the yokes 28 is preferably accomplished as shown in FIGS. 9 and 10. The yoke 28 is made from two halves 224L, 224R held together by a number of screws 226 forming the hollow section shown in FIG. 10. Bushings 228 may be provided as shown in FIG. 11 to reduce sliding friction between yoke 28 and support shafts 208. Passing through clearance holes 230 in each yoke 28 are a number of rotatable keyed drive shafts 232 and a nonrotatable screw-threaded drive shaft 30. A conventional chain sprocket 236 is threadably engaged with fixed screw shaft 30 between halves 224 as shown in FIG. 10. Another chain sprocket 238 is engaged for rotation with one of the keyed shafts 232 passing through yoke 28. A conventional endless roller chain 240 encircles the sprockets 236, 238. Therefore, upon driven rotation of keyed shaft 232, sprocket 236 is caused to rotate by the chain connection just described. Such rotation advances sprocket 236 along threaded shaft 30 thereby causing lateral movement of yoke 28 because the confinement of sprocket 236 within the yoke.

As shown in FIG. 9, only one keyed shaft 232 is belt connected to screw shaft 30 through sprockets 236, 238 in any one yoke 28. The remaining keyed shafts 232 merely pass through the clearance holes 230. However, in the next adjacent yoke 28, a different shaft 232 will be connected to screw shaft 30. Thus, it can be seen that a keyed shaft 232 must be provided for each yoke 28 that is used; in the present example, eight are used. In this manner the yokes 28 operate independently of each other so that they can be positioned as required across the width of the machine.

Obviously, the chain connection just described is not essential. For example, a screw-threaded shaft could be substituted for each keyed shaft 232 and fixed mating screw threads could be provided in the appropriate opening in yoke 28. Then, as the screw shafts are rotated, the yoke would advance along the screw shaft as previously described. However, to overcome any tendency of the yokes to bind on the support shafts 208, the first of the two constructions is preferred since the screw shaft 30 can be centrally located as shown so that all of the yokes react in the same manner.

The arrangement for driving the keyed shafts 232 in one direction is shown in FIGS. 12, 13, and 14. As particularly shown in FIG. 13, screw-threaded shaft 30 is fixed between housings 168 by, for example, a collar 242 held to the housing 168 by screws 244. Keyed shaft 232 extends through a bearing 246 into the interior of housing 168.

The drive path for operating the keyed shafts 232 is diagrammatically illustrated in FIGS. 12 and 15. As shown in FIG. 13, an input shaft 246 extends coaxially outward from the center of screw shaft 30 but is not connected thereto. Input shaft 246 is supported for rotation in bearings 248 secured in housing 168 and includes necked-down end portions 250 and 252. End 252 is connected by a conventional shaft coupling 254 to the output shaft 256 of an electric motor 258 which is secured by screws 262 to faceplate 260 for housings 168.

A spur tooth gear 264 is secured in any convenient fashion to the other end 250 of input shaft 246 for meshing engagement with a similar gear 266 which is mounted on bearings 268 and 270 for rotation about a stud 272 fixed in housings 168 by screws 274 substantially as shown in FIG. 13.

Gear 266 includes another gear 276 integrally connected therewith which meshes with a gear 278 mounted on bearings 280 for rotation about a necked-down end portion 282 of keyed shaft 232. The outboard end 284 of gear 278 is secured in the conventional manner to one-half 286 of an electric clutch 288. The opposite half 290 of clutch 288 is secured for rotation with the end 282 of keyed shaft 232.

Each of the keyed shafts 232 are identical and are provided with the gear 278 and clutch 288 as just described. In addition, the gears 278 are all positioned in meshing engagement with each other as diagrammatically illustrated in FIG. 12 so that all the gears 278 are driven by gear 276. Of course, alternate ones of gears 278 rotate in opposite directions. To compensate for this condition, corresponding alternate ones of screw shafts 30 are provided with left-hand screw threads instead of right-hand threads. Thus, the sprockets 236 on the screw shafts 30 will all advance in the same direction at the same time. Alternatively, idler gears (not shown) may be provided between gears 278 in the known manner so that keyed shafts 232 will all rotate in the same direction. In this event, the threads on shafts 30 would all slope in the same direction.

Clutch 288 can be of any one of several conventional electric types well known in the art which can be selectively energized so that the half 290 is driven by the half 286 when the clutch is energized. Thus, by referring to FIGS. 12 and 13, it can be seen that when motor 258 is energized, each of the keyed shafts 232 is rotated through the gear train previously described when the clutch associated with the shaft is energized. Thus, by selectively energizing the clutches 288, any one of the keyed shafts 232 can be rotated to advance the yoke 28 associated with the particular shaft toward the left side of the machine as viewed in FIG. 2.

Motor 258 runs continuously (during setup) in the same direction. To move yokes 28 toward the right-hand side of the machine, a continuously running motor 258L is provided on the left-hand side of the machine as illustrated in FIG. 16. This motor 258L runs continuously (during setup) in the opposite direction from motor 258. The gear train described and shown in FIG. 13 is duplicated on the left side of the machine as shown in FIGS. 15 and 16. The parts shown in these figures that correspond to those in FIGS. 12 and 13 have the suffix L added thereto.

Accordingly, it can be seen that selective energization of clutches 288 and 288L determines the direction that the yokes 28 will move. This will be discussed in greater detail in the "controls" portion of the specification.

It should be observed that other gears shown in FIGS. 12, 13, and 14 are not used on the left side of the machine. The reason for this will become evident as the description progresses.

The ratios of the various gears just described can be selected in accordance with well-known principles to achieve the desired advancing velocity of the yokes.

The construction and mounting of the faceplates 260 and 292 for housing 168 is obvious from the figures so that no further description is deemed necessary.

It should be equally obvious from the foregoing that the number of revolutions made by the keyed shafts 232 determines the distance advanced by the yokes 28 along screw shafts 30. Potentiometers 294 and 296 are provided for each keyed shaft 232 to provide an electrical error signal for comparison with a dialed in setting, to be subsequently described. Potentiometer 294 is a single-turn dual potentiometer while 296 is a single potentiometer.

The manner in which the potentiometers are connected to the keyed shafts 232 is shown in FIG. 14. Keyed shaft 232 includes a gear 298 secured for rotation with a necked-down portion 300 of the shaft. Potentiometer 294 is secured to a mounting bracket 302 fastened to faceplate 292. A potentiometer drive shaft 304 is mounted for rotation in bushings 306 provided in housing 168 in coaxial alignment with the output shaft 308 of potentiometer 294. A conventional shaft coupling 310 connects output shaft 310 with drive shaft 304. A compound gear 312 is secured for rotation with drive shaft 304; the gear includes two sets of spur gear teeth 314 and 316.

Another compound gear 318 is secured for rotation with idler shaft 320 in driving engagement with both gear 298 and compound gear 312 by means of two sets of gear teeth 322 and 324. Idler shaft 320 is mounted for rotation in bushings 306 provided in housing 168 in the same manner as described for drive shaft 304.

A second potentiometer drive shaft 326 is mounted for rotation in bushings 306 provided in housing 168. The second potentiometer 296 is secured to mounting bracket 302 in the same manner as potentiometer 294. Another shaft coupling 310 connects output shaft 310 of potentiometer 296 to shaft 326. A gear 328 having a set of gear teeth 330 is secured for rotation with shaft 326; the gear teeth 330 are in driving engagement with teeth 314 of compound gear 312.

By following the drive path shown in FIG. 14, it can be seen that potentiometer 294 is rotated in accordance with the rotation of keyed shaft 232; likewise, potentiometer 296 is rotated in accordance with the rotation of potentiometer 294. The ratio of the gears is selected in accordance with well-known engineering principles to result in the desired number of revolutions of the potentiometers.

The drive path just described and illustrated in FIG. 14 is identically duplicated for all of the keyed shafts 232 as will appear from reference to FIG. 12. Thus, as each keyed shaft 232 is rotated by selective engagement of its associated clutch 288, electrical signals are produced by the potentiometers which are used to control the position of yokes 28 along screw shaft 30.

An AC tachometer 301 is also provided for each keyed shaft 232 to provide an electrical signal 180° out of phase with

the potentiometers to balance the system and prevent hunting. This will be described in greater detail in the "controls" portion of the specification. As shown in FIG. 14, the end portion 282 of keyed shaft 232 extends beyond clutch 288 and is connected to the output shaft 303 of tachometer 301 by another shaft coupling 254. Tachometer 301 may be mounted to the face of plate 260 as shown.

The potentiometers 294, 296 and tachometer 301 are operative regardless of the direction of travel of yokes 28. Accordingly, they, and the various gears associated therewith, are not needed in the housing shown in FIGS. 15 and 16.

The pusher plates 32 previously referred to are illustrated in greater detail in FIGS. 7, 8, and 18. A pusher 32 is provided for each pair of shafts 16, see FIG. 1, of which only one will be described since they are substantially identical.

Pusher 32 surrounds each shaft of the pair of shafts 16, being snugly but slidably mounted to one of the shafts but having an enlarged opening 332 surrounding the other shaft that is adjustable toward and away from the one shaft to compensate for such adjustment. A pair of rotatable threaded screw shafts 334A, 334B, pass through a correspondingly threaded bushing 336 secured in plate 32. Screw shafts 334 prevent rotation of the pusher 32 around the one shaft 16 so that the opening 332 remains concentrically spaced from the other shaft 16. Thus, it can be seen that upon simultaneous rotation of screw shafts 334, the pusher 32 will advance across the machine while pushing the heads 24 in front of it to their parked position.

A clearance hole 338 is provided in pusher 32 to permit adjustment shaft 88 to pass through it.

The pusher 32 is preferably hollow, being made in two halves 340L, 340R held together by a number of threaded screws 226 such as described for yokes 28.

The drive arrangement for advancing the pushers 32 is shown in FIGS. 17 and 18. The arrangement is similar to that shown in FIG. 4 for driving the pairs of shafts 16.

A reversible electric drive motor 342 is secured to the main frame 12L so that its output shaft 343 is concentric with the axis of rotation 69 of spool 10. An electric clutch 344 includes one-half 345 secured for rotation with output shaft 343 and another half 346 upon which a spur tooth gear 347 is mounted for rotation.

A pair of mounting studs 78 are secured in trunnion 116L by threaded screws 80. Spur tooth gears 350 are rotatably mounted on bearings 352 which are secured to studs 78 by washers 82 and screws 84. The studs 78 are located so that gears 350 will mesh with gear 347.

The screw shafts 334 are mounted for rotation in bearings 354 which are secured in the spool frame 18L. Gears 356 are secured for rotation with necked-down portions 358 provided on shafts 334 by washers 360 and screws 362. Gears 356 are proportioned to mesh with each other and with one of the idler gears 350 as best shown in FIG. 15. Thus, it can be seen that gears 356 are driven by motor 342 through clutch 344, drive gear 347, and idler 350. Since, as previously explained, shafts 334A and 334B are threaded in opposite directions, both shafts 334 advance the pusher plates 32. The pusher plates 32 are advanced until the heads being pushed thereby butt against stops 34, then the clutch 344 slips whereupon its operating button may be released. Another operating button is provided to reverse rotation of motor 342 to return the pusher plates 32 to their original position against the double-face heads 22D, 24D; the clutch 344 again slips and the pushbutton 75 may be released. Operation of the pushbuttons will be described in detail in the "controls" portion of the specification.

It can also be seen in FIG. 17 that when spool 10 is rotated from position A to position B, gears 356 for the screw shafts 334 associated with the pairs of shafts 16A, 16B are brought into mesh with idler gears 350. When spool 10 is returned to position A, the gears 356 associated with pairs of shafts 16C and 16D are brought into mesh with idler gears 350. This arrangement is similar to that described in FIG. 4 for driving the pairs of shafts 16.

Controls

Following is a general description of the electrical controls for positioning heads 22, 24 across the machine by yokes 28.

FIG. 20 shows a block diagram of an analog servosystem which can be used for positioning the yokes 28. This particular control is described for a machine capable of slitting the web into five widths at one time and providing two scores in each width. The number of servocontrols required to do this is 16; 10 controls are used for positioning the scoring heads 24 and six controls are used for positioning the slitting heads 22. Only one control will be described since they are identical.

In FIG. 20, the blocks are identified as follows:

M1 = mixer for read-in and readout signals

E = electronic switching network

R = error signal from modified Kelvin-Varley bridge

K1 = chopper

K2 = band-pass filter

K3 = preamplifier

M2 = mixing point for amplified error signal and tachometer feedback

G1 = class AB driver

G2 = phase-sensitive demodulator

G3 = power amplifier

G4 = two DC clutches

G5 = gear train (shown in FIGS. 12, 13, 14, 15, and 16)

H1 = AC tachometer

H2 = two feedback potentiometers of which one is a dual single-turn potentiometer

B1 = modified Kelvin-Varley bridge.

To set an order, the desired slitting and scoring head positions are dialed directly into a bank of conventional rotary switches. Each servosystem covers a total travel of 90 inches, for example. These switches read directly in inches from a zero index line and are part of a modified Kelvin-Varley bridge circuit (see FIG. 21). Two potentiometers H2 (identified by numbers 294, 296 in FIG. 14) are geared indirectly to the heads and feed a signal back to this bridge that is directly proportional to the position of the heads from stop 34 (FIG. 2). Potentiometer 294 is a combination in one housing of two potentiometers as shown in FIG. 21. This signal is then compared to the signal dialed into the bridge. The resulting difference between these two signals is referred to as the "error" signal. This DC error signal is then preferably converted to an AC signal by chopper K1 since DC amplifiers are somewhat unstable. DC excitation is used on this bridge because of quadrature voltage generated due to the inductance and capacitance of the bridge resistors and associated wiring. Quadrature voltage cannot be nulled out by the feedback signal from the tripotentiometer network since it is 90° out of phase with respect to the reference voltage. The net result is amplifier saturation. This AC signal of 60-cycle frequency is fed into band-pass filter K2. This is desirable due to the large amount of noise content of most choppers. The signal is then passed through preamplifier K3, where the voltage of this signal is amplified to a sufficient value to feed mixing network M2. Mixing network M2 combines the amplified error signal from K3 with the tachometer feedback signal from H1. This will be discussed later.

These combined signals then are fed to class AB driver G1. After amplification, this signal is then fed to phase-sensitive demodulator G2. This converts the AC signal back to DC. This is done because the drive clutches G4 (288 and 288L in FIGS. 13, 14, and 16) used in this system are operated by DC current. Power amplifier G3 further amplifies the signal to operate clutches G4. Two clutches are used to reverse direction of the yokes 28. The particular clutch that operates depends upon the polarity of the original error signal. The clutches 288 and 288L operate keyed shaft 232 that positions the head setting yokes 28. The source of power for the clutches are continuously running AC motors 258 and 258L driving the clutches through gear train G5 (see FIGS. 13 and 16). Feedback tachometer H1 (301 in FIG. 13) is also powered by the keyed shafts 232. The signal amplitude from the tachometer is velocity dependent and is fed to mixer net-

work M2. This tachometer signal is generally 180° out of phase with the amplified error signal, and is used for stabilizing purposes. The amplitude of the tachometer signal is adjusted so that it is below the amplitude of the error signal so as not to be the controlling signal. This enables the servosystem to be adjusted anywhere from critically damped to over damped.

Referring now to FIG. 21, a four section Kelvin-Varley bridge modified as shown in FIG. 21 includes two followup potentiometers for the "read-in" and "readout." The entire unit is energized with a 100 volt DC supply. As mentioned before, this is necessary to eliminate quadrature voltage due to the various stray capacitances and inductances of the resistors and wiring. The "read-in" and "readout" device is split into two parts. Sections A, B, and C of the Kelvin-Varley bridge form part of the "coarse" positioning circuit, and section D forms part of the "fine" positioning circuit. A 10-turn potentiometer (Pot A) is used to form the rest of the coarse positioning circuit, and two single-turn potentiometers in a single housing 294 are phased 180° with respect to each other to form the rest of the fine positioning circuit. The coarse potentiometer covers the entire 90 inches and each fine potentiometer covers 1 inch/half revolution. Both fine potentiometers make a total of 45 revolutions for 90 inches. Therefore the gear ratio between the coarse pot and load is 10 to one and is 4.5 to one between the coarse pot and fine pot. Two fine pots are used instead of one to avoid the ambiguity that exists due to a 1° to 3° gap between the ends of the potentiometer winding. Therefore, only half of each winding is used. The two fine potentiometers alternately control the final position of the yokes 28, depending upon the position of the selector switch SB of section B of the bridge. As selector switch SB is rotated, wiper W7 alternates in position from terminal T56, which is the wiper of Pot C, to terminal T57, which is the wiper of Pot B. The setting of switch SC to set in 1/16-inch changes also sets section D to a similar 1/16-inch setting. For each setting of section A, a 10-inch change is made. When wipers 1A and 1B are respectively set on terminals T9 and T11, a setting of anywhere from 0 to 10 inches in 1/16-inch increments can be made by properly positioning the rest of the selector switches. This picks off the lowest voltage across section A. If this selector switch is then moved to terminals T8 and T10 of section A, a setting of anywhere from 10 inches to 20 inches can be made, etc.

This section A divides the voltage E-1 appearing across it into nine selectable parts. The entire impedance of section B is approximately the same as that of section A looking in between wipers 1A and 1B. This is proper impedance matching.

Section B divides the 10-inch settings into 1-inch increments. This section divides the voltage E-2 appearing across it into 10 selectable parts. If the wipers 2A and 2B of selector switch SB are correspondingly set on terminals T21 and T23, a setting of anywhere from 0 to 1 inch in 1/16-inch increments can be made, depending on where selector switch SB is set. The impedance of section C is chosen to approximate the impedance of section B looking in between wipers 2A and 2B.

Section C divides the 1-inch settings into 1/16-inch increments. When wiper W3 is set on terminal T39, zero-sixteenth of an inch is set in. Terminal T38 corresponds to one-sixteenth of an inch, etc. This section divides the voltage E-3 appearing across it into 15 selectable parts. Once a final setting has been made, a voltage appears between wiper W3 and ground of the coarse setting section. Another voltage E-4 appears between the wiper W8 of Pot A to ground, depending upon the position of the yoke that is being set. A difference voltage is then obtained between wiper W3 and the wiper W8 of Pot A. This signal, after amplification, then drives the servosystem until the difference voltage is reduced to near zero. At this point an electronic switching circuit E transfers the control of the servo to the fine circuit from the coarse circuit when the system has been positioned to within plus or minus one-quarter inch of the desired location. There appears a voltage E-5 between

wiper W6 to ground. Another voltage E-6 appears between wiper W7 and ground. Either Pot B or Pot C will provide the error signal at wiper W7 depending upon the position of selector switch SC. This error signal then is amplified to operate the clutches 288 and 288L and the servo system then positions the yoke 28 to the final 1/16-inch setting.

FIG. 22 shows the electronic switching circuit that switches the positioning system from coarse to fine. Two parallel diodes D1 and D2 are used back to back to form a bilateral nonlinear resistance element. Using the shown, each diode has a back bias of 1.5 volts. As the coarse signal increases, this back bias is overcome and the coarse signal appears at the output terminals TC and TB. If the signal is positive at terminal TD with respect to terminal TB, current flows through R4, D1, R2, through the load and then to terminal TB. If the polarity of the error signal is negative at TD with respect to TB, then current flows from TB to TD through the load, from terminal TC through R2, D2, through R5 and then to terminal TD. As the coarse signal decreases, the output signal at terminals TC and TB decreases in a nonlinear fashion due to diodes D1 and D2. At this point the fine signal takes over. Depending on polarity, the fine signal passes from terminal TA through R1, R2 to terminal TC and then to the load and then to terminal TB.

This composite signal is then fed into a mechanical chopper circuit such as that shown in FIG. 23. Sixty-cycle AC line voltage is applied to terminals TG and TH of the excitation coil. This coil then vibrates the vibrating contactor at line frequency which alternately makes contact with the DC signal through terminals TC and TB. The result is essentially a square-wave output whose amplitude is a direct function of the DC input signal amplitude and whose phase is a function of the polarity of the input signal, the phase of the AC excitation signal, and the phase shift between the excitation signal and the vibrator mechanical motion. R6 is used for current limiting of the contacts of the chopper.

This AC signal is then passed to a band-pass filter shown in FIG. 24. The particular filter used is a UTC BM 160, made by United Transformer Company of 150 Varick St., New York, N.Y. The actual circuitry is not known but the following characteristics apply. This filter has a gain of 2:1 at the center frequency of 60 cycles. There is a 2-db. attenuation at ± 3 percent of the center frequency. It also has an attenuation of 40 db. per octave. This filter is used to eliminate chopper noise and most of the harmonics generated by the chopper. Choppers normally generate a semisquare wave, and the filter makes it more or less sinusoidal.

The error signal is then passed to a preamplifier shown in FIG. 25. The output from the band-pass filter is across terminals TL and TM of FIG. 24. The input to the preamplifier is across terminals TL and TM with terminal TO and a common ground. Potentiometer F is provided to balance the quiescent DC current between transistors Q2 and Q3. As the signal level at TL becomes more negative with respect to terminal TO, Q1 will start to conduct and current increases from R9 to the emitter, collector junction of Q1 and through R8. This increases the base current of Q2 which causes its emitter to collector current to increase. Current flow is from the 10-volt supply through R13, Pot F, Q2, R10, and to the -10-volt supply. As this current flow increases, the collector of Q2 or terminal Q1 swings negative with the collector of Q3, or terminal TR. If the polarity of the signal at terminal TL starts to swing positive, Q1 conducts to a lesser extent. At the same time the signal at terminal TM will start to go negative; Q4 and Q3 will conduct more current and the signal at TR goes negative with respect to terminal TQ. The net result is a sine wave between terminals TQ and TR, providing the input is sinusoidal.

A transistor Q5 is preferred as a constant current source, since differential amplifiers are somewhat prone to drift.

The output of the preamplifier (FIG. 25) is then fed to the class AB driver as shown in FIG. 26. The input signal to the driver is across terminals TQ and TR. Blocking capacitors C1 and C2 prevent DC from the preamplifier from getting into

the driver. This could cause amplifier saturation. As terminal TQ goes positive with respect to TR, transistor Q6 starts to conduct more than Q5. As the polarity of the signal reverses, Q5 conducts more than Q6. The net result is an alternating voltage across the primary of transformer T2. The two diodes D3 and D4 provide a signal path back to ground. The 3-volt supply as fed through R18 biases this amplifier into a class AB operation. R19 is a common emitter-resistor for stabilizing purposes.

The signal from the output of the class AB driver is fed to the phase-sensitive demodulator via transformer T2 as shown in FIG. 27. The dots shown above each transformer winding in FIG. 27 indicate the instantaneous polarity of the AC signal across that particular winding. For example, when the instantaneous polarity of the signal on terminal TT1 of transformer T2 is positive, the polarity of the signal at terminal TT4 and also terminal TT5 of the same transformer is also positive. For example, if, at time zero, the instantaneous polarity of the signal at terminal TT1 of transformer T2 is positive, the instantaneous polarities at TT4 and TT5 are positive also. Assuming the reference signal at terminal TT1 of transformer T3 is also positive, the polarity at terminals TT4 and TT5 of transformer T3 is also positive. As can be seen, the two signals across the secondary windings of both transformers T2 and T3 add. The current path is then from terminals TT6 to TT4 of transformer T3, through TT6 to TT4 on transformer T2, then through Diode D5, to R20 and C3 through Diode D8, and back to terminal TT6 of transformer T3. At the same time the two signals across terminals TT5 and TT7 of transformers T2 and T3 subtract. Assuming that the signal developed across the two secondaries of transformer T2 is less than that across the two secondaries of transformer T3, the current path is from terminals TT7 to TT5 on transformer T3 through TT5 to TT7 on transformer T2, through diode D12, R21 and C4, D9, and back to TT7 of transformer T3. At time T=one-half cycle later, the instantaneous polarity of the signal at terminal TT3 of transformer T2 is positive, and positive also at terminals TT6 and TT7 of transformer T2. At the same time, the polarities at TT6 and TT7 of transformer T3 are also positive. Again the signals at TT4 and TT6 of transformers T2 and T3 add and the signals of TT5 and TT7 of transformers T2 and T3 subtract. The current path of the upper half of the demodulator is from terminals TT4 to TT6 of transformer T2, TT4 to TT6 of transformer T3 through diode D6, through R20 and C3 and through D3 and back to TT4 of transformer T2. The current path of the lower half of the demodulator is from terminals TT5 to TT7 of transformer T3, through D10, R21 and C4, through D10, through TT7 to TT5 of transformer T2 and back to terminal TT7 of transformer T3. As can be seen, these signals subtract.

The net result is that the positive charge on capacitor C3 is greater than that on capacitor C4. If the opposite polarity of the signal on the primary of transformer T2 exists as compared to that on the primary of transformer T3, the positive charge on capacitor C4 exceeds that of capacitor C3. This network then converts its AC input to a full-wave rectified DC output across capacitors C3 and C4. The two capacitors C3 and C4 essentially reduce the ripple content of this network to near zero.

This output from the demodulator is then fed to the power amplifier as shown in FIG. 28. Output terminal TU of the demodulator corresponds to terminal TU of the power amplifier; terminal TV corresponds to terminal TV of the power amplifier. As terminal TV of the power amplifier goes positive with respect to TU, Q7 conducts more current than Q8. A point is reached when the increase in current flow through Q7 turns on clutch CL1 (288, FIGS. 13, 14).

CL1 remains energized until the initial error signal is nulled. When terminal TU becomes positive with respect to TV, a point is reached where Q8 energizes clutch CL2 (288L of FIG. 16). CL2 remains energized until the error signal is again nulled. The base current of Q7 to CL1 passes from R22, through the emitter to base junction of Q7, through diode D13

and to ground. The current to energize CL1 passes from the 28-volt power supply through R22, emitter to collector junction of Q7, through CL1 and back to the negative side of the 28-volt power supply. A similar path of current energizes clutch CL2. Diodes D13 and D14 short out the collapsing voltage of CL1 and CL2 whenever they are turned off. This prevents damage to any of the components due to these large transients. These two clutches then drive the slitter-scoring yokes until the positioning potentiometers null out the error signal voltage.

Operation

A schematic illustration of the controls for setting up and operating the slitter-scoring is shown in FIG. 29.

An order is finished using single-wall heads on shafts 16A and 16B, the slitter-scoring and double-backer are slowed down to, for example, 90 feet per minute lineal velocity. The web 20 is then cut and the double-backer is immediately slowed to about 30 feet per minute. This opens up a gap between the web ahead of the cut and the slowly advancing web behind the cut.

When the relatively fast-moving web clears the slitter-scoring, the machine is stopped by turning rotary switch P62 to OFF which stops motor 62. The spool 10 is then indexed 90° clockwise to position B by pushbutton P18 which energizes solenoid 138 to retract spool locking pin 134 (See FIG. 5) and energizes indexing motor 130. When indexing is complete, pushbutton P18 is released which stops motor 130 and deenergizes solenoid 138 to let locking pin 134 extend into the tapered opening 136 provided in subframe 18R. Thus, the shafts 16C and 16D have been brought into position for engagement with the slowly advancing web 20. The slitter-scoring is started by turning rotary switch P62 to ON which starts main drive motor 62. As the slowly advancing web 20 passes through the slitter-scoring, both it and the double-backer may be brought up to normal production speed.

To begin repositioning the heads 22, 24 along shafts 16A, 16B for the next order, the heads are first moved to the "park" position against stops 34 on the right side of the machine as viewed in FIG. 2. To do this, the yoke assemblies 26U, 26L are opened, if they are in the closed position, by pushbutton P24 which energizes motor 198 to run in the proper direction to open the yoke assemblies, the pushbutton P24 being released when the yoke assemblies reach the limit of their travel. Thereafter, pushbutton P20 is depressed to release the hydraulic pressure that locked heads 22, 24 to shafts 16A, 16B. Once this pressure is released, pushbutton P22 is depressed to pull in clutch 344 and energize reversible motor 342 in the proper direction to move pusher 32 against the heads to move them against stops 34. When the heads butt against the stops 34, the clutch 344 slips and pushbutton P22 is released thereby deenergizing both motor 342 and clutch 344.

Assuming that a single-wall order is to be set up on shafts 16A, 16B, the pushers 32 must be returned to the left side of the machine against double-wall heads 22D, 24D. This is done by depressing pushbutton P23 which pulls in clutch 344 and energizes motor 342 in the proper direction (reverse to direction operated by pushbutton P22) to return pushers 32 to the left. When pushers 32 butt against heads 22D, 24D, clutch 344 slips and the pushbutton P23 is released.

The next step in setting up is to dial in the positions to which the heads are to be moved by yokes 28. This is done by turning selector switches SE 1 through 16, as previously described in the "controls" portion of the specification, to the desired setting. Only those switches needed for the number of heads to be used are set; the remaining ones are preferably left on the zero setting. The switches SE control the setup position of the heads on both the pairs of shafts 16A, 16B. The selector switches SE must be used for the yokes in a sequence beginning from the inboard yoke to the outboard yoke so that the yokes do not jam each other.

After the foregoing settings are made, the yoke assemblies are closed by depressing pushbutton P25 to energize motor

198 which then rotates in the proper direction to close the yoke assemblies. When they are fully closed, the pushbutton is released. When the yoke assemblies are closed, the yokes 28 engage the heads 22, 24 in the park position.

5 The next step is to depress "start" pushbutton P17 to energize motors 258 and 258L. When this button is pushed, it energizes relay 1 CR which keeps contacts 1 CR closed until "stop" pushbutton P26 is depressed. Thus, motors 258, 258L remain running even though pushbutton P17 is released. Motors 258 and 258L supply power to keyed shafts 232 through the clutches 288 that are subsequently energized. Motor 258 rotates keyed shafts 232 in one direction and motor 258L rotates them in the other so that yokes 28 can be moved in either direction across the machine.

15 Actual movement of the yokes 28 is initiated by turning the knobs of position switches PS to ON. The switches are switched ON in the sequence to cause the yokes 28 to move out of the "park" position in the proper order to avoid jamming one yoke against the next. The signal from the switches PS is amplified and processed by amplifier AF. The servosystem previously described under "controls" then automatically positions the yokes according to the dimensions set in on selector switches SE. The amplifier AF automatically selects the proper clutches 288 or 288L to rotate keyed shafts 232 in the required direction until the yokes 28 are correctly positioned. Visual observation will show when the yokes have been finally positioned. When positioning has been completed, pushbutton P21 is depressed to supply hydraulic pressure to the interior of shafts 16A, 16B to lock the heads 22, 24 to the shafts. After this, all of the switches PS that were turned ON are turned to OFF.

20 At this time, pushbutton P25 is depressed to energize motor 198 in the proper direction to open yoke assemblies 26U, 26L to their fully open position as previously described. Thereafter, the yokes 28 are returned to the single-wall park position against stops 34 by dialing in a zero setting on the selector switches SE and operating positioning switches PS as previously described. The positioning switches are operated in the proper sequence to return the yokes to the park position in the order required to prevent jamming. When the yokes are returned to park, the position switches PS are turned to OFF. The yoke assemblies 26U, 26L may remain in the open position or may be moved to the closed position if desired by pushbutton P25. Setup of the single-wall heads is now complete and motors 258, 258L may be stopped by pushbutton P26.

25 To return the yokes 28 to the park positions, overriding pushbuttons (not shown) can be used if desired to bypass the selector switches SE and directly energize clutch 288L and motor 258L.

30 Assuming now that the order being run with the shafts 16C and 16D is completed and the shafts 16A and 16B just set up are to be used on the next order, the slitter-scoring and double-backer are slowed to 90 feet per minute as before, the web 20 is transversely cut and the double-backer is immediately slowed to 30 feet per minute. As the fast-traveling web clears the slitter-scoring, it is stopped by turning rotary switch P62 to OFF. With the yoke assemblies 26U, 26L in the open position, 35 by depressing pushbutton P24 is necessary, the spool 10 is indexed to position A by depressing pushbutton P19 to energize solenoid 138 and motor 130 in the proper direction. Thus, shafts 16A, 16B are brought into position for engagement with advancing web 20. When pushbutton P19 is released, the spool 10 is locked in place by solenoid 138. Rotary switch P62 is turned to ON to start motor 62 for driving the slitter-scoring which may then be brought up to normal operating speed when the double-backer is accelerated.

35 In order to set up shafts 16C, 16D for double-wall operation 40 on the next order, the single-wall heads 22, 24 must be returned to their park position. Accordingly, pushbutton P27 is depressed to release the hydraulic pressure within these shafts. Pushbutton P22 is depressed to energize clutch 344 and motor 342 in the proper direction to move pushers 32 to the right to move the heads 22, 24 against stops 34 at the end

of the park position. When clutch 344 slips, button P22 is released. Since double-wall heads 22D, 24D are to be positioned, pusher 32 is left against the single-wall heads.

With yoke assemblies 26U, 26L already in the open position, yokes 28 may be sent to the left-hand or double-wall side of the machine by dialing in the double-wall park setting, that is, the maximum dimensions indicated on the selector switches SE. Pushbutton P17 is depressed to start motors 258, 258L for providing power to keyed shafts 232 as previously described.

Actual motivation is accomplished by depressing the position switches PS. When the yokes 28 butt against the stops 34 on the left-hand side of the machine, the position switches PS are turned to OFF. Yoke assemblies 26U, 26L are then closed as previously described by depressing pushbutton P25.

The selector switches SE are then set to the desired dimensions for the position of the double-wall heads 22D, 24D to be set up. Again, only those switches are set for the desired number of heads to be used; the position switches PS are turned to ON in the reverse sequence from the single-wall heads to cause the yokes 28 to move from the park position in the proper order to prevent jamming. Again, the selector switches SE must have been set in a sequence for the yokes beginning from the inboard side towards the outboard side to prevent jamming. The servosystem previously described automatically positions the heads as it did for the single-wall heads.

When visual observation reveals that the heads are in their final setup position, pushbutton P28 is depressed to provide hydraulic pressure to the shafts 16C, 16D to lock the heads 22D, 24D in position. The position switches PS are then turned to OFF.

The yoke assemblies 26U, 26L are then opened by pushbutton P24. Yokes 28 are returned to the single-wall or right side of the machine against stops 34 by dialing in the single-wall park settings on selector switches SE. Motivation occurs when the position switches PS are turned ON; these switches are turned OFF when the yokes butt against stops 34. Motors 258, 258L are then stopped by pushbutton P26. Again, yoke assemblies 26U, 26L may be left in the open position or closed if desired.

When the double-wall order just set up for is to be run, indexing of spool 10 is accomplished as previously explained and the next order to be run with shafts 16A, 16B is set up using either single-wall or double-wall heads in the manner described in the foregoing description.

At the end of the double-wall order being run with shafts 16C, 16D, spool 10 is again indexed with yokes 26U, 26L in the open position. The heads 22D, 24D are unlocked by pushbutton P27. Since the pushers 32 were left on the right-hand side of the machine against the single-wall heads 22, 24, the pushbutton P23 is depressed to move the pusher to the left to move heads 22D, 24D back to the double-wall park position against stops 34. When the heads butt against the stops, clutch 344 will slip and pushbutton P23 may be released. If a new single-wall order is to be set up, the pushers 32 are left in this position against the double-wall heads. If a double-wall order is to be setup, the pushers 32 must be moved to the right side of the machine against the single-wall heads as previously described. Thereafter, whatever setup is desired can be performed in the manner described.

The foregoing description covers the operation of the various combinations of setups that may be performed on the various sets of shafts. Although FIG. 29 is a schematic illustration showing only the essential elements of the controls, those skilled in the art will readily understand the operation of the various parts and be able to connect them in the required manner.

The preferred arrangement has been described in the foregoing specification. If desired, both the slitting heads 22 and scoring heads 24 may be mounted to one pair of cooperating shafts supported for rotation about axis 69. Thus, the shafts may be indexed to the inactive B position where the yokes 28 are operative to reposition the heads whereupon they may be returned to the operative position A. In this con-

struction, the web 20 would not be permitted to enter the slitter-scoring until the shafts are returned to the operative position.

Another arrangement could include two pairs of cooperating shafts with one pair in the operating or active position while the heads on the other pair are being positioned along the shafts in the inactive position.

Although the web 20 has been described as corrugated paperboard, the invention is equally useful in acting on webs of other materials where it is desirable to be able to preset the lateral position of tool elements. Furthermore, the tool elements need not be of the rotary type nor must there be more than one. For example, paper, plastics, and other materials may be slit by knife blades extending from a holder and through the web. The only requirement is that the tools or toolholder be engageable by the yokes 28.

It should be further understood that the tool elements need not be removed to an inactive position for presetting. For example, if only one pair of shafts is used, the pair may remain in a fixed position with the yokes 28 being movable to an inactive position during active engagement of the tool elements with the web and movable into an active position in engagement with the tool elements when they are not acting on the web. In this construction, the web would preferably not be acted upon during the presetting period to avoid damage to the web by the tool elements moving across the path of travel of the web. Accordingly, sufficient time would be required to preset the tools before a new portion of the web entered the machine.

It should be understood that the pushers 32 can be operated to move the heads to the park position while the shafts are in position for engagement with a web; however, the web should not be passing through the slitter-scoring at this time and enough time should be allowed for parking the heads before the advancing web enters the slitter-scoring.

We claim:

1. Apparatus for acting on an advancing web, comprising: support means adjacent said web; at least one tool element slidably supported by said support means for operative engagement with said web;

40 presetting means adjacent said tool element engageable therewith for moving said element to selected locations across the path of advance of said web when said tool is out of operative engagement with said web, said presetting means being disengageable from said tool element when the tool is in operative engagement with said web; and

45 pusher means slidably mounted on said support means for moving said tool against a stop provided at the end of a parking area on said support means extending beyond one edge of said web;

50 said presetting means engageable with said tool in said parking area for moving said tool to a selected location across the path of advance of said web and disengageable from said tool at said selected location to enable said presetting means to be returned to said parking area for reengagement with said tool when the same is returned to said area by said pusher means;

55 whereby said selected location is established from the point of engagement between said presetting means and said tool.

2. The apparatus of claim 1, and in addition:

a second parking area provided on the opposite end of said support means from said parking area and extending beyond a second edge of said web; and an auxiliary tool slidably mounted on said support means and stored in said second parking area during operation of said tool element;

60 said presetting means selectively engageable with either of said tool element or said auxiliary tool for moving either of said tools to a selected location across the path of advance of said web and disengageable from either of the tools so engaged at said selected location to enable said presetting means to be returned to said parking area.

3. Apparatus for acting on an advancing web, comprising:

support means adjacent said web;
 a spool supported by said support means and rotatable from a first position to a second position about an axis extending transverse to the path of advance of said web;
 said spool including at least one pair of driven shafts extending parallel to said axis upon which rotary tool elements are slidably mounted for cooperative engagement with said web;
 presetting means engageable with said rotary tool elements when the same are in said second position upon rotation of said spool for positioning said tool elements along said shafts; and
 pusher means slidably mounted on said pair of driven shafts for moving said rotary tool elements against a stop provided at the end of a parking area on said shafts extending beyond one edge of said web when said spool is in said second position;
 said presetting means engageable with said rotary tool elements in said parking for moving said elements to selected locations along said shafts across the path of advance of said web and disengageable from said elements at said preselected locations to enable said presetting means to be returned to said parking area for reengagement with said tool elements when the same are returned to said area by said pusher means.

4. The apparatus of claim 3, and in addition:
 a second parking area provided on the opposite end of said shafts from said parking area and extending beyond a second edge of said web; and
 auxiliary rotary tool elements slidably mounted on said shafts and stored in said second parking area during operation of said rotary tool elements;

5. Apparatus for acting on an advancing web, comprising:
 support means adjacent said web;
 a spool supported by said support means and rotatable from a first position to a second position about an axis extending through said web and transverse to its path of advance;
 said spool including a first pair of driven shafts extending parallel to said axis upon which rotary tool elements are slidably mounted for cooperative engagement with said web when said spool is in said first position and out of cooperative engagement with said web when said spool is in said second position;
 said spool further including a second pair of shafts extending parallel to said axis upon which rotary tool elements are slidably mounted out of cooperative engagement with said web when said spool is in said first position and in cooperative engagement with said web when said spool is in said second position; and
 presetting means engageable with the rotary tool elements on said second pair of shafts when said spool is in said first position and engageable with the rotary tool elements on said first pair of shafts when said spool is in said second position for positioning said tool elements along their respective shafts when the tool elements are out of cooperative engagement with said web;

6. The apparatus of claim 5, and in addition:
 pusher means slidably mounted on each of said first and second pairs of driven shafts for moving the tool elements mounted thereon against a stop provided at the end of a parking area on said shafts extending beyond one edge of said web;

said presetting means engageable with said tool elements in said parking area for moving said elements to selected locations along said shafts across the path of advance of said web and disengageable from said elements at said selected locations to enable said presetting means to be returned to said parking area for reengagement with said tool elements when the same are returned to said area by said pusher means.

7. The apparatus of claim 6, and in addition:
 a second parking area provided on the opposite end of said first and second pairs of shafts from said parking area and extending beyond a second edge of said web; and
 auxiliary rotary tool elements slidably mounted on each of said pairs of shafts and stored in said second parking area during operation of said rotary tool elements;

8. The apparatus of claim 5 wherein said presetting means comprises:
 at least one support shaft supported by said support means parallel to said axis in juxtaposition to the rotary tool elements on either of said first or second pairs of shafts when said tools are out of cooperative engagement with said web;

9. The apparatus of claim 8, and in addition:
 opening and closing means connected to said support shaft for selectively moving the yokes mounted thereon into and out of engagement with said tool elements to enable said yokes to be moved to either of said parking areas after said tool elements have been positioned along said pairs of shafts.

10. The apparatus of claim 9 wherein said opening and closing means is selectively operable to move said yokes to an open position out of engagement with said tool elements prior to rotation of said spool and to move said yokes to a closed position in engagement with said tool elements after rotation of said spool for providing clearance between said yokes and said tool elements on respective ones of said pairs of shafts during rotation of said spool.

11. The apparatus of claim 8 wherein said drive means for each of said yokes includes:
 a drive shaft extending through said yoke and operatively connected to a source of rotation at one end thereof;
 a first sprocket secured for rotation with said drive shaft and held captive within a hollow portion of said yoke;
 a threaded shaft extending through said yoke;
 a second sprocket threadably engaged with said threaded shaft and held captive within said hollow portion of said yoke; and
 an endless chain encircling said first and second sprockets for rotating said second sprocket upon rotation of said drive shaft to advance said second sprocket along said threaded shaft;

12. The apparatus of claim 5, and in addition:
 main drive means for driving said first pair of shafts when said spool is in said first position and for driving said second pair of shafts when said spool is in said second position;

said main drive means including a drive source positioned externally of said apparatus and provided with an output shaft extending into said spool coaxial with said axis; first gear means connected to said first pair of shafts and in operative engagement with a drive gear means connected to said output shaft when said spool is in said first position; 5 second gear means connected to said second pair of shafts out of operative engagement with said drive gear means when said spool is in said first position; and indexing means for rotating said spool from said first position to said second position to move said first gear means out of operative engagement with said drive gear means and to move said second gear means into operative engagement with said drive gear means; whereby said first and second pairs of shafts are driven by said drive means during operative engagement of said first and second gear means respectively with said drive gear means. 10 13. The apparatus of claim 5, and in addition: edge alignment means for moving said spool axially along said axis to maintain said tool elements in lateral alignment with said web with respect to its path of advance; said edge alignment means including power means secured in a stationary position with respect to said spool and having an output member connected to said spool; and signal means responsive to lateral misalignment of said web for providing a signal to said power means; said power means directing said output member in a direction corresponding to the misalignment of said web until said tool elements are in alignment with said web. 15 14. Apparatus for acting on an advancing web, comprising: support means adjacent said web and including main frame portions beyond the edges of said web; a spool supported by said main frame portions and rotatable from a first position to a second position about an axis extending through said web and transverse to its path of advance; 20 said spool including a first set of two pairs of driven coating shafts disposed diametrically opposite said axis along the path of advance of said web of which the lower shafts of each pair are beneath said web and the upper shafts of each pair are above said web when said spool is in said first position; said spool further including a second set of two pairs of coating shafts disposed diametrically opposite said axis and normal to the path of advance of said web when said spool is in said first position; 25 said first and second sets of shafts including rotary tool elements mounted thereon adapted for cooperative engagement with said web; presetting means for positioning the tool elements on each pair of shafts of said second set of shafts when said spool is in said first position and for positioning the tool elements on each pair of shafts of said first set of shafts when said spool is in said second position; 30 whereby the tool elements positioned by said presetting means are brought into cooperative engagement with said web and the tool elements previously in cooperative engagement with said web are brought into engagement with said presetting means upon rotation of said spool. 35

15. The apparatus of claim 14, and in addition: a first parking area on one end of said first and second sets of shafts beyond the edge of said web for storing said tool elements out of cooperative engagement with said web; auxiliary rotary tool elements slidably mounted on said first and second sets of shafts; a second parking area on the opposite end of said first and second sets of shafts opposite said one end and beyond the edge of said web for storing said auxiliary tool elements out of cooperative engagement with said web; and pusher means slidably mounted on each of said first and second sets of shafts for moving either of the said tool elements or auxiliary tool elements on said shafts to said first or second parking areas respectively; 40 said presetting means selectively engageable with either of said rotary tool elements or said auxiliary rotary tool elements for moving the same to selected locations across the path of advance of said web when they are out of cooperative engagement with said web and disengageable from either of the tools or auxiliary tools at said selected locations to enable said presetting means to be returned to said first or second parking areas prior to rotation of said spool. 45 16. The apparatus of claim 15 wherein said presetting means comprises: a pair of support shafts supported by said main frame portions parallel to said axis in juxtaposition to the rotary tool elements or auxiliary rotary tool elements on either of said first or second sets of shafts when said tools are out of cooperative engagement with said web; a yoke for each said rotary tool element or each said auxiliary tool element and slidably mounted on said pair of support shafts and engageable with the ones of said tool elements out of cooperative engagement with said web; and drive means connected to said yokes for moving them across said support shafts to selected locations thereby positioning selected tool elements engaged by said yokes. 50 17. The method of selectively presetting first and second sets of rotary tool elements for subsequent cooperative engagement with an advancing web, comprising the steps of: moving said first set of rotary tool elements from a first position in cooperative engagement with said web to a second position out of cooperative engagement with said web; moving said second set of rotary tool elements from said second position to said first position into cooperative engagement with said web; 55 moving said first set of rotary tool elements to a parking area beyond an edge of said web; bringing a presetting means into engagement with said first set of rotary tool elements in said parking area; energizing said presetting means for moving selected ones of said first set of rotary tool elements to selected locations transverse to the path of advance of said web; disengaging said presetting means from said selected ones of said first set of rotary tool elements; 60 moving said presetting means to said parking area; and thereafter, moving said first set of rotary tool elements to said first position in cooperative engagement with said web and moving said second set of rotary tool elements to said second position out of cooperative engagement with said web. 65
